(57) **CLAIM**

I claim the ornamental design for a bone-conducted 3D massage pillow, as shown and described.

DESCRIPTION

FIG. 1 is a front side perspective view of a bone-conducted 3D massage pillow showing my new design;

FIG. 2 is a top plan view of FIG. 1;

FIG. 3 is a bottom plan view FIG. 1;

FIG. 4 is a front elevational view FIG. 1;

FIG. 5 is a rear elevational view FIG. 1;

FIG. 6 is a right side elevational view FIG. 1; and,

FIG. 7 is a left side elevational view FIG. 1.

1 Claim, 5 Drawing Sheets
